**RALPH G. NULL, OF INDIANAPOLIS, INDIANA, ASSIGNOR TO G. & J. TIRE COMPANY,
A CORPORATION OF NEW JERSEY.**

DESIGN FOR A PNEUMATIC VEHICLE-TIRE.

48,571.

Specification for Design.

Patented Feb. 15, 1916.

Application filed October 28, 1915. Serial No. 58,493. Term of patent 14 years.

To all whom it may concern:

Be it known that I, RALPH G. NULL, a citizen of the United States, residing at Indianapolis, county of Marion, and State of Indiana, have invented a new, original, and ornamental Design for Pneumatic Vehicle-Tires, of which the following is a specification, reference being had to the accompanying drawing, forming a part thereof, in which:

Figure 1 is a plan view of a portion of a tire showing my improved design; Fig. 2 is a side elevation of the same; and Fig. 3 is a cross-sectional view of the same.

I claim:

The ornamental design for a pneumatic vehicle tire, as shown.

Signed this 21 day of October, 1915.

RALPH G. NULL.
